UNITED STATES PATENT OFFICE.

LOUIS WIDMAYER, OF NEW BRITAIN, CONNECTICUT, ASSIGNOR TO P. & F. CORBIN, OF SAME PLACE.

DESIGN FOR DRAWER-PULLS.

Specification forming part of Design No. 6,724, dated June 24, 1873; application filed June 10, 1873.

To all whom it may concern:

Be it known that I, LOUIS WIDMAYER, of New Britain, in the county of Hartford and State of Connecticut, have invented a Design for Drawer-Pulls, &c., of which the following is a specification:

The general shape of this article is that of a half box, with a flange upon three sides for attaching to the drawer or other article, leaving one side open for the insertion of the fingers when used as a pull. The same article may be used as a nosing or catch for a box lock or latch.

The nature of the design is fully shown in the annexed drawing, wherein—

Figure 1 is an elevation; and Fig. 2 is an edge view partially in section.

The flange *a* is ornamented with square or Grecian ornaments, as represented. The sides *b*, of the box portion, are ornamented with raised spears and intervening scallops. The beveled

portions *d*, between the sides *b* and top *e*, are ornamented with the angular or Grecian figures or pattern shown, and the top *e* is ornamented with a sunken panel having raised scrolls and leaflets, as represented.

The general shape and configuration of this article is represented clearly, the angles being beveled or made diagonal.

I claim as my invention—

1. The design of the shape and configuration of the flange, sides, and top with the beveled angles, as represented.

2. The design of the ornamentation upon the top *e*, sides *b*, flange *a*, and bevel *d*, substantially as represented.

Signed by me this 3d day of June, A. D. 1873.

LOUIS WIDMAYER.
